UNITED STATES PATENT OFFICE.

GEORGE H. FERNALD, OF NORTHEAST, PENNSYLVANIA.

THILL-COUPING.

SPECIFICATION forming part of Letters Patent No. 695,097, dated March 11, 1902.

Application filed March 28, 1901. Serial No. 53,277. (No model.)

To all whom it may concern:

Be it known that I, GEORGE H. FERNALD, of Northeast, in the county of Erie, in the State of Pennsylvania, have invented new and useful Improvements in Thill-Couplings, of which the following, taken in connection with the accompanying drawings, is a full, clear, and exact description.

This invention relates to improvements in thill-couplings, and particularly to an antirattler and quick-shift mechanism.

The object of this invention is to provide means whereby the antirattler mechanism may automatically adjust itself to any size or form of thill-couplings.

The further object of this invention is to so combine the hinge-pin, bearing-plate, and spring for the antirattler as to permit the same to be readily withdrawn or inserted in operative position when desired, said plate serving to hold the hinge-pin in operative position from lateral movement or displacement.

To this end the invention consists in the combination, construction, and arrangement of the parts of a thill-coupling, as hereinafter fully described, and pointed out in the claim.

Referring to the drawings, Figures 1, 2, and 3 are respectively top plan, side elevation, and front face views of a thill-coupling embodying my invention. Fig. 4 is an isometric view of the detached hinge-coupling, showing the bearing-plate and antirattler-spring as mounted thereon. Fig. 5 is an isometric view of the detached bearing-plate.

Similar reference characters indicate corresponding parts in all the views.

A represents an ordinary clip mounted upon an axle A' and secured thereto by a suitable clip-plate a and clamping-nuts a'. The clip is provided with the usually-separated ears 1, having apertures for receiving the coupling-pin, presently described.

B is an ordinary thill-strap, having an eye b inserted between the ears 1 and having its aperture alined with the apertures of the ears 1.

The parts just described may be of any desired form or size and are herein shown to illustrate the operation of my invention, which consists of a coupling-pin 2, a bearing-plate 3, and a spring 4.

The coupling-pin 2 is preferably U-shaped, having one of its arms, as 5, adapted to be inserted in the apertures of the ears 1 and eye b for coupling the thill-strap to the clip. The opposite arm 6 of the bar 2 is preferably of less length than the arm 5 and is provided with a reduced portion 7 for forming separated shoulders 8 and 9, said arm 6 being normally disposed in a plane beneath the ears 1 and eye b, or, in other words, is separated a sufficient distance from said ears and eye to permit the hinge-pin to be rocked upon the arm 5 when it is desired to remove the thills 65 from the clips A.

The bearing-plate 3 is similar in face view to the plate which forms a portion of the subject-matter of my former application, Serial No. 50,443, filed March 9, 1901, being provided with laterally-projecting arms 10, having opposite inclined edges 11, converging toward each other, the opposite ends of said plate being extended beyond the inclined edges 11. This bearing-plate 3 is provided with a forwardly-projecting lug 12, having an aperture 13, which receives the reduced portion 7 of the arm 6 of the coupling-pin 2, said aperture having an open front side for forming suitable shoulders 14. This bearing-plate 75

is usually formed of malleable iron or similar metal, and the shoulders 14 are normally separated a sufficient distance to receive the reduced portion 7 of the arm 6, said shoulders being compressed toward each other in 85 the manner seen in Figs. 2, 3, and 5 for securing the bearing-plate to the said reduced portion 7, it being understood that the shoulders 14 are sufficiently pliable to permit the same to be hammered or otherwise compressed for the purpose just described. The shoulders 8 and 9 being of greater diameter than the aperture 13, it is evident that said bearing-plate is prevented from lateral displacement and is retained in position by the 95 arm 6.

The spring 4 is similar to that set forth in my former application, Serial No. 50,443, being provided with coils 15, which are mounted upon the projecting arms 10 of the bearing-plate 3 and are arranged to engage the inclined edges 11 of said arms 10 when the spring is tensioned to its operative position, as seen in Figs. 1, 2, and 3. The oppo-

site ends of the coils extend forwardly and rearwardly beyond the front and rear faces of the coils, the front ends of said coils being united to each other, and are provided with a 5 concave engaging face 16 and an intermediate downwardly-extending loop 17, which is also concave, for engaging the rear face of the thill-strap B, or, rather, of the eye b, the opposite ends of said coil being provided with 10 a suitable link 18, which is movably connected to said rearwardly-extending arms of the coils and is adapted to engage or interlock with the upper face of the clip-plate a, it being understood that when the rear ends 15 of the coils 15 are elevated and the link 18 is interlocked with the clip-plate a that the coils 15 are slightly contracted and firmly engage the opposite inclined edges of the arms 10, and when said spring is in its normal position 20 the coils are open sufficiently to permit the arms 10 to be readily inserted into or withdrawn from the coils 10. It is further evident that when the spring 4 is tensioned the rear face of the intermediate portion of 25 the bearing-plate 3 is forced against the front edge or end of the clip-plate a and that the upper end of the bearing-plate is also forced into engagement with the rear face of the forwardly and upwardly extending arms of the 30 spring.

When the parts of my invention are assembled or placed in operative position, as seen in Figs. 1, 2, and 3, the concave engaging face of the forwardly and upwardly extending arm 35 of the spring is registered with the rear face of the eye b and the opposite arms of the spring are tensioned upwardly and the link 18 is slipped over and engaged with the upper face of the rear end of the plate a, thus 40 holding the spring in its tensioned position, the bearing-plate being free to slide or move along the front edge of the clip-plate a in order that the upwardly-extending arm of the spring which engages the rear face of the eye 45 b may readily center itself or adjust itself to the contour of said eye. This combination and construction of my invention forms a particularly simple means for preventing the rattle of the hinge connection between the 50 thill strap and clip and at the same time

forms a quick shift for permitting the thills or a pole to be readily placed in operative position or removed therefrom.

It will be noted that the hinge-couplings, bearing-plate, and antirattler-spring are all 55 connected to each other, are readily assembled, and can be manufactured and sold as an article of manufacture at a minimum cost and applied to any form of thill-coupling.

The operation of my invention will now be 60 readily understood upon reference to the foregoing description and the accompanying drawings, and it will be noted that some change may be made in the detail construction and arrangement of the parts of my invention without departing from the spirit thereof—as, for instance, the lug 12 may be unprovided with the transverse division in the wall of the aperture 13 and the free end of the arm 6 may be provided with a removable shoulder, as a nut, for preventing the lateral displacement of said bearing-plate. 70

Having thus fully described my invention, what I claim, and desire to secure by Letters Patent, is—

In an antirattler for thill-couplings, the combination of a clip having separated ears, a thill-strap having an eye inserted between the ears, a substantially U-shaped bar having one arm inserted through the ears and 80 eye of the thill-strap, a bearing-plate carrying upward and downward extensions, arms having outwardly-inclined edges, formed intermediate said upward and downward extensions, an apertured split lug formed integral with said plate to receive the other arm of said substantially U-shaped bar carrying a reduced portion, a spring carrying coils engaging the arms of the plate, an upwardly-extending curved loop carrying an intermediate downwardly-extending curved loop engaging the rear face of said thill-strap, and means whereby said springs are suitably connected together. 85 90

In witness whereof I have hereunto set my hand this 18th day of March, 1901.

GEO. H. FERNALD.
